UNITED STATES PATENT OFFICE.

HENRY N. KERR, OF PHILADELPHIA, PENNSYLVANIA.

OIL-LAMP BURNER.

1,291,547.

Specification of Letters Patent. Patented Jan. 14, 1919.

Application filed April 26, 1915. Serial No. 23,825.

To all whom it may concern:

Be it known that I, HENRY N. KERR, a citizen of the United States, residing in Philadelphia, Pennsylvania, have invented certain 5 Improvements in Oil-Lamp Burners, of which the following is a specification.

My invention relates primarily to that class of oil lamps in which the flame from the wick is caused to heat an incandescent mantle of the usual type, although some of the features of my invention are also applicable to lamps in which the light is derived from the exposed flame. The objects of my invention are to direct to the flame an air 10 supply in such volume and so distributed as to insure complete, and consequently smokeless, combustion; to so construct the burner as to provide convenient access to all parts of the same for cleaning or other purposes; 15 to so mount the mantle as to provide for ready removal and replacing of the same and ready adjustment of it to its proper position in respect to the flame from the wick; to provide for thorough ventilation of that 20 portion of the oil font which is above the level of the oil therein; to prevent splashing of oil from the filling nozzle of the oil font such as might otherwise be caused by careless handling of the lamp; to regulate the 25 force of the flame so as to accord with the character of the mantle which is being used, and to prevent disruption of the flame by the outward projection of air currents against the inner portion of the same adjacent to 30 the upper end of the wick.

These objects I attain in the manner hereinafter set forth, reference being had to the accompanying drawings, in which—

Figure 1 represents a vertical section of so 40 much of an oil lamp of the incandescent mantle class as to properly illustrate my invention;

Fig. 2 is a transverse section of part of the same on the line $a-a$, Fig. 1;

Fig. 3 is a detached vertical section of the air supplying dome and central guide tube viewed from the same point as in Fig. 2;

Fig. 4 is a detached vertical sectional view of the wick carrier viewed from the same 50 point as in Fig. 1;

Fig. 5 is a detached vertical sectional view of the removable upper member of the air supplying dome viewed from the same point as in Fig. 1;

Fig. 6 is a detached vertical sectional view

of part of the mantle holder and its support;

Fig. 7 is a top view of the valved air distributing cap which surmounts the central 60 guide tube;

Fig. 8 is a top view of the valve removed from said cap;

Fig. 9 is a detached vertical sectional view of the chimney holder.

Fig. 10 is a vertical sectional view of a 65 modified form of wick carrier, and

Fig. 11 is a horizontal section of said carrier with the wick mounted thereon and with the central guide tube in place therein.

In Fig. 1 of the drawings, 1 represents the 70 upper part of the oil font which is usually of metal and has at the top a central internally threaded depending neck 2, and at one side an upwardly projecting filling nozzle 3 with screw cap 4 which has therein openings 75 5 for ventilating the oil font above the level of oil therein and providing for the inflow of air as the volume of oil decreases. Within the screw cap, at some little distance from the inner ends of the openings 5, is mounted 80 a deflector 6, the latter serving to prevent splashing of oil through the openings in the cap which might otherwise be caused by careless handling of the lamp.

Into the internally threaded neck 2 at the 85 top of the lamp is screwed the externally threaded tubular neck 7 at the base of the air supplying dome 8, the latter having a detachable upper member 10, the lower portion of which fits snugly within the upper 90 portion of the dome 8, and is vertically supported upon cleats 24 engaging slots 23 in said upper member, as shown in Fig. 10, the upper portion of said member being contracted in diameter so as to bear upon the 95 outer side of the tubular wick 12, as shown in Fig. 1, and having below said contracted bearing portion an external shoulder 26 for a purpose hereinafter set forth.

The dome 8 is perforated, as shown at 8^a, 100 for the free flow of air to the outside of the wick 12, as shown in Fig. 1, and (through the split portions of the wick hereinafter referred to) to the upper portion of the oil font, and to an air space within a wick carrier 15, hereinafter mentioned.

The dome 8 is provided with lateral channels 13 for supporting and supplying air to the interior of the central guide tube 9, the wick 12 being split at opposite sides, as 110

shown in Fig. 1, so as to straddle the casings of said channels and permit said wick to be readily raised and lowered.

Surrounding the upper portion of the central guide tube 9, is an air chamber 14, the casing of which is perforated at top and bottom so as to permit free inlet of air at the bottom of the chamber and free outlet of air at the top of the same, and surrounding 10 and guided in its vertical movement by the outer casing of this air chamber is the tubular upper portion of the wick carrier 15 to which the wick 12 is secured by means of an external fibrous wrapping 16, as shown 15 in Fig. 2.

The tubular wick carrier 15 has opposite vertical openings 15^a formed therein, as shown in Fig. 4, so that the lower portion of the wick carrier presents opposite 20 cave legs 17 and 18 which are contracted in diameter in respect to the upper portion of the carrier, as shown in Fig. 4, and bear upon the opposite sides of the guide tube 9, as shown in Fig. 1, said legs being disposed 25 one on each side of the casing of the air channels 13, and the lower ends of the legs being maintained in proper relation to one another by means of a transverse brace plate 61, as shown in Figs. 1, 2 and 4.

30 The leg 18 is perforated so as to form a rack for engagement with the teeth of a spur wheel 19 which is disposed on the inside of the central guide tube 9, and projects through an opening in one side of the same, as shown in Fig. 1. The spur wheel 19 is carried by a shaft 20 free to turn in bearings 21 on the base of the dome 8, and within the channels 13, as shown in Figs. 2 and 3, said shaft having a projecting end 40 provided with a knurled or roughened knob 22 whereby it may be readily turned in one direction or the other to raise or lower the wick carrier and wick.

The contracted upper end of the upper member 10 of the dome terminates at the top in an outwardly flaring flange 25 which extends slightly above the top of the wick when the latter is at its normal height, and thus serves to prevent overflow, to the outer 50 side of the member 10, of any free oil which may be carried up by the wick, such free oil being retained by the flange 25 and held against the wick until it is consumed.

Upon the external annular shoulder 26 55 (Fig. 5) of the upper dome member 10 rests a ring 27 (Fig. 9) perforated as at 28, and having at its inner edge an upwardly projecting flange 29 which bears against that portion of the member 10 immediately above 60 the shoulder 26, as shown in Fig. 1. The outer portion of the ring 27 engages and supports the internally shouldered portion 30 of an annular chimney holder 31, which has, around its inner edge, an upstanding 65 vertical flange 32 and around its outer edge

a ring 33 with upwardly projecting spring fingers 34 for bearing upon the lower portion of the glass chimney 35 which rests upon the holder 31, the latter having, inside of the chimney, perforations 36 for 70 permitting an upflow of air between the chimney and the mantle in order to prevent overheating of the chimney which might cause fracture of the same.

The internal flange 32 of the chimney 75 holder bears against the inside of the lower portion of the mantle support 11 and serves to guide the latter in its vertical movements of adjustment, such movements being imparted to it by means of a ring 37 having 80 an internally threaded depending neck 38 which is screwed upon the externally threaded portion of the lower dome member 8 of the burner, as shown in Fig. 1, and serves as a support for legs 39 depending 85 from the mantle support 11, as shown in Fig. 6, these legs passing through suitable openings in the chimney holder 31, as shown in Fig. 1.

The mantle holder consists of a tapered 90 ring 40 (Figs. 1 and 6) fitting snugly to but removable from the tapered upper portion of the support 11 and having sockets 41 for receiving the lower ends of the legs of a yoke 42, the mantle 43 (shown by dotted lines in Fig. 1) being suspended by means of a loop 44 from the transverse top member of said yoke and the lower free edge of the mantle being engaged and held in place by cleats 45 on the top of the throttling flange 56 which projects inwardly from the top of the ring 40, and surrounds the flame opening 55, as shown in Figs. 1 and 6.

Fitting snugly within the central guide tube 9 at the top of the latter is an inverted 105 cup-shaped cap 46 having in its side wall, perforations 47 and in the top other perforations 48, and on the underside of the top of the cap is a valve 49 carried by a central stem 50 which can be turned by means of a 110 head 51 above the top of the cap, as shown in Fig. 1. In the valve 49 are formed two sets of openings 52 and 53, as shown in Fig. 8, the openings of one set being of lesser diameter than those of the other set so that 115 by proper adjustment of the valve either set of openings may be caused to register with the openings 48 in the top of the cap and the area for the upflow of air from the top of the cap and into the central portion of the mantle 43 can thus be varied as desired.

When the lamp is burning, air flows 120 freely inward through the perforations 8^a in the dome 8 to the outside of the wick and through the split portions of the latter into 125 the font 1 above the oil therein, air also passing through the openings 15^a of the wick carrier 15 into the air space below the air chamber 14, through which it rises and issues through the perforations in the top 130

of the same, thereby deflecting upwardly the air jets issuing laterally from the side openings 47 in the cap 46, thereby preventing said jets from impinging upon the inner 5 surface of the flame adjacent to the wick with force enough to disrupt said flame.

Free access of air to the outside of the flame is provided by the openings 28 in the chimney holder supporting ring 27 and there 10 is also a free flow of air to the inside of the flame through the air chamber 14, and the openings 47 and 48 of the cap 46, perfect and smokeless combustion being thereby insured, while, at the same time, overheating of those 15 parts of the burner which are in proximity to the flame is prevented. The force with which the gases of combustion impinge upon the inner side of the mantle depends in great measure upon the vertical relation of the 20 throttling flange 56 in respect to the top of the wick, and this can readily be regulated by adjustment of the movable support 11 after the lamp has been lighted, thereby regulating the force of the gases to accord with 25 the coarse or fine mesh of the mantle employed.

It will be noted that the various parts of the burner are fitted together so as to be readily detachable one from another and 30 while this feature of my invention is not absolutely necessary it is a desirable one as it facilitates cleaning, inspection and repair of the burner, and when the upper member of the dome is detachable from the lower member 35 the wick can be introduced into the font from above without unscrewing the dome, the wick carrier in this case being without the bottom brace 61.

The free flow of air through the perforated dome into and from the font prevents 40 heating of the oil therein, or the accumulation of combustible gas in the font above the oil.

In Figs. 10 and 11 I have shown a modification of my invention in which instead of the air chamber 14 surrounding the central tube at the top and the wick carrier greater in diameter at the top than at the bottom, I use a wick carrier 15^b of the same diameter 45 from top to bottom but presenting a corrugated cross section, so that air channels 14^a are formed both between the wick carrier and the central tube 9, and between the wick carrier and the wick 12, either set of these 55 channels being sufficient to convey the proper amount of air to the inside of the flame.

I claim:

1. The combination, in an oil lamp burner, 50 of a central guide tube, a wick, and a wick carrier around which the upper portion of said wick is secured, said wick carrier comprising an upper tube portion and depending side legs bearing upon and guided by the central guide tube, one of said legs being 55 perforated so as to form a rack.

2. The combination, in an oil lamp burner, of a central guide tube, a wick, a wick carrier expanded in diameter at its upper end, and means for causing upward flow of air between said central guide tube and the expanded upper end of said wick carrier. 70

3. The combination, in an oil lamp burner, of a central guide tube having a casing surrounding the upper portion of the same and inclosing an air chamber, and a wick carrier comprising an upper portion, bearing upon said air chamber casing, and depending, inwardly bent, side legs, bearing upon the lower portion of said central guide tube, one of said legs being perforated so as to 75 80 form a rack.

4. The combination, in an oil lamp burner, of a central guide tube having an air chamber casing surrounding the upper portion of the same, and a wick carrier comprising 85 an upper portion bearing upon the said air chamber casing and a contracted lower portion forming an air space below said air chamber, the wick carrier having an opening therein through which air can enter said air 90 space.

5. The combination, in an oil lamp burner, of a chimney holder, a mantle, a mantle support above said chimney holder, legs depending from said support and passing through 95 the chimney holder, and a vertically adjustable mounting for the lower end of said legs.

6. The combination, in an oil lamp burner, 100 of a mantle, a mantle holder having a downwardly projecting and outwardly flaring flange, a mantle support having an upwardly projecting and inwardly flaring flange adapted to receive the flange of the mantle holder, and, below the same, a downwardly projecting cylindrical flange, means 105 for engaging the latter to guide the mantle support in its vertical movement, and means for effecting such vertical movement.

7. The combination, in an oil lamp burner, 110 of a central guide tube, a wick carrier guided thereon and having an upper portion of greater diameter than the guide tube so as to form an air space between them, an opening in said carrier through which air can 115 pass into said air space, and a wick having a split portion which registers with said opening.

8. The combination, in an oil lamp burner, 120 of a central air supply tube having a top closure with openings therein, and an adjustable valve for varying the effective area of said openings.

9. The combination, in an oil lamp burner, 125 of a central air supply tube with a top closure therefor having vertical openings therein, and an adjustable valve having a plurality of sets of openings therein, the openings of the different sets being of different diameters and said valve being movable so as to 130

bring either set of its openings into register with the openings in the top closure of the air supplying tube.

10. The combination, in an oil lamp burner,
5 of a wick, a wick support, a guide tube there-
for, and an air chamber casing surrounding
the upper portion of said tube, said casing
being perforated at top and bottom so as to
provide for a flow of air through the same
10 from that portion of the burner below the

casing to the inside of the flame above the 15
wick.

In testimony whereof, I have signed my
name to this specification, in the presence of
two subscribing witnesses.

HENRY N. KERR.
